(57) **CLAIM**

What is claimed is the ornamental design for an identification card holder, as shown and described.

DESCRIPTION

FIG. 1 is a perspective view of an identification card holder, showing the new design in a closed position;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a perspective view thereof, illustrated in an open position;

FIG. 9 is a front elevational view of FIG. 8;

FIG. 10 is a rear elevational view of FIG. 8;

FIG. 11 is a right-side elevational view of FIG. 8;

FIG. 12 is a left-side elevational view of FIG. 8;

FIG. 13 is a top plan view of FIG. 8; and,

FIG. 14 is a bottom plan view of FIG. 8.
